CLAIM

The ornamental design for a combined computer systems handling cart and storage unit, as shown.

DESCRIPTION

FIG. 1 is a perspective view of a combined computer systems handling cart and storage unit showing my new design;

FIG. 2 is a top plan view thereof;

FIG. 3 is a front elevational view thereof; and

FIG. 4 is a left side elevational view thereof.

The rear of the unit is flat and unornamented.

FIG. 1

FIG. 2

FIG. 3

FIG. 4
